Patented Mar. 30, 1915.

UNITED STATES PATENT OFFICE.

RALPH E. GOULD, OF HARTFORD, CONNECTICUT.

SETTING DEVICE FOR SULKY-PLOWS.

1,133,558.

Specification of Letters Patent.

Patented Mar. 30, 1915.

Application filed March 2, 1911. Serial No. 611,859.

To all whom it may concern:

Be it known that I, RALPH E. GOULD, a citizen of the United States, and a resident of Hartford, in the county of Hartford and State of Connecticut, have invented a new and Improved Setting Device for Sulky-Plows, of which the following is a specification.

My invention relates to the class of 10 wheeled plows, that is, one in which the plow or plows are supported upon wheels that move over the surface being plowed, and the object of my invention among others is to provide a device of this class by means 15 of which a plow may be readily moved to position to plow a furrow and in which the depth of the furrow may be accurately determined.

One form of device in the construction 20 and use of which the objects herein above set out may be attained is illustrated in the accompanying drawings in which—

Figure 1 is a side view of so much of a sulky plow only as is needed to illustrate 25 my invention. Fig. 2 is a top view of the same.

In the accompanying drawings, the numeral 6 indicates the axle of a plow arranged to be supported as by means of 30 wheels 7, shown in dotted outline. This axle is offset as at 8 and on this offset portion a plow-beam 9 is pivotally mounted as by means of a box 18 with a plow 10 supported at the lower rear end of the beam, the front 35 end 11 being arranged for attachment of a whiffle-tree or like means for the connection of a draft animal, or other means for propelling the plow.

A hand lever 12 is secured as by means of 40 a pin 5 at one end to the axle 6 and the frame is supported by this lever, it being understood that there is a lever at each side of the frame in the device herein illustrated and described which embodies two plows. 45 This frame includes an arch 13, each lower end 14 of which is pivotally secured to a lever 12, and a brace 15 extends from each end of the arch forward, being attached at its forward end to a member 16 connected 50 with the arch 13 and thus forming a rigid part of the frame and also a support for the seat 17.

A curved rack 19 is mounted on the pin 20 that pivotally unites the hand lever 12 and the frame, herein above described, this 55 rack being supported as by means of arms

21, notches on the underside of the rack being adapted for engagement with a detent 22 on a detent bar 23 mounted to slide lengthwise on the hand lever and pivotally connected at its upper end to a grip lever 24 in the usual manner. The rack is secured to the frame in any suitable manner. All the parts herein above described are of old and well known construction and the operation in which the 60 handle 12 if unrestrained will move to the right or backwardly will be readily understood by those skilled in the art and further, it being remarked that the fulcrum of the lever 12 is in the axle 6, and the plow 10 65 with its beam 9 is supported by the crank or off set portion 8 of the axle. The lever is secured to the axle 6 so that it is evident that if the axle is turned the lever will turn with it. The weight of the frame and parts 70 supported thereon is transmitted to the lever 12 through the pin 20, so that the weight of the frame and parts supported thereby is opposed to the weight of the beam and plow. Therefore, the weight of 75 the plow and beam 9 being greater than that of the frame and parts supported thereby, the handle 12 when released will be thrown rearwardly in a manner common to plows of this well known construction. 80

In the operation of plows of this class both hands of the driver are frequently occupied to properly guide the horses and for other purposes, and it thus becomes desirable to operate the mechanism for "setting" 85 the plow" by other than manual means, and the mechanism now about to be described provides means for accomplishing this result in an effectual manner, and the plow may be set to any depth required with certainty as to the operation of the parts to 90 attain this end.

In carrying out my invention I provide a latch lever 28 that may be pivotally secured at one end to the rack 19 as by means of a 100 pivot pin 29, passing through a slot 30 in said lever. The pin 29 is adapted to engage either one of a number of holes 31 in the rack 19 thus furnishing an adjustable pivotal point of attachment for the rack. 105

A foot lever 32 is rotatably supported as by the part 16 and the brace 15, this lever having a crank pedal 33 by means of which the lever is operated by the foot of the driver. The end of this lever has a crank 110 arm 34 pivotally connected with the end of the latch lever, in the form shown this arm

being adapted to pivotally engage any one of a number of holes 35 in the latch lever.

A detent trip pin 36 projects from the side of the bar 23 and underlies a detent trip 37 projecting from the side of the latch lever 28. As shown herein this detent trip is in the form of a curved rib overlying the pin, from which it will be seen that as the lever is moved downward this detent trip 10 encountering the trip pin will move the detent bar 23 to disengage the detent 22 from its notches hereinbefore described.

In order to stop the movement of the lever 12 and hence the vertical movement of the 15 plow the rear end of the detent trip 37 is so located that the trip pin 36 will run off said end, and being thus relieved will allow the detent 22, under the force of the spring 38, to immediately reengage one of its notches 20 and stop the movement of the lever 12 at such time, and the provision of means for locating the pivot 29 in different holes 31 enables the disengagement of the detent trip pin from the detent trip with the lever 25 in different positions, and the plow may thus be located in different vertical positions to plow a furrow of greater or lesser depths.

It will be found desirable in many instances to control the movement of the lever 30 handle, and as one means for attaining this end I mount a train of gears on said handle, this train including a pinion 27 and an intermeshing gear 26, the latter meshing with a gear 25 secured to rotate with one of the 35 wheels 7, said gear and wheel being shown in dotted outline in Figs. 1 and 2. A toothed rack is located on the under edge of the latch lever 28, these teeth being adapted to mesh with the teeth of the pinion 27 when the latch is moved downward 40 to disengage the detent, as hereinbefore described, it being understood that when this arrangement is employed the disengagement of the detent should occur just before the 45 meshing of the teeth of the pinion and rack. When the teeth are so engaged the movement of the lever will be controlled by the movement of the pinion 27 which may be geared to rotate at the proper speed.

50 It will be understood that the mechanism above described may be duplicated as desired, and especially in connection with each of the levers located at opposite sides of the frame, and especially that it is not essential to the invention that the gears be employed to regulate the rate of movement of the lever, as these gears may be dispensed with when desired and the lever be permitted to move under the weight of the plow, 55 or other conditions existing in the machine.

The operation of the device is as follows:—The parts being in the position shown in Fig. 1 with the plow raised, pressure upon the pedal 33 will cause the latch

lever 28 to be swung downward on its pivot 65 29. In this movement of the latch lever the detent trip 37 encounters the detent trip pin 36, moving the detent bar 23 and disengaging the detent 22 from the notches at the lower edge of the curved rack 19. The construction of the parts and the distribution of the weight will at this time tend to move the lever 12 to the right or backwardly, in an old and well known way common to plows of this construction, and should the gear 70 and pinion 26—27 not be employed this backward movement of the handle would continue until the pin 36 moves off at the end of the trip 37, when the detent 22 will at once engage the notches in the under side 75 of the rack 19 and thus stop the downward movement of the plow. By employing the gear and pinion 26—27 the rate of this rearward movement of the lever will be controlled by the rate of movement of the pinion 80 27 and a movement of the lever at an undesired rate will thus be prevented, the pinion 27 passing from engagement with the teeth on the latch lever 28 at just about the time of disengagement of the trip pin from 85 the detent trip.

While I have shown and described herein one form of device for carrying out my idea, this may be departed from to a greater or lesser extent without avoiding the invention, 95 and I do not, therefore, limit myself to the exact construction of mechanism herein shown and described.

I claim:—

1. A plow with means for supporting it, 100 said parts being arranged to normally permit the plow to move to a lower position, and said supporting means comprising means for raising and lowering the plow, means for holding the plow in a predetermined position, means for releasing said holding means to lower the plow and to automatically reengage said holding means at different predetermined points to determine the depth of a furrow to be plowed. 105

2. A plow with means for supporting it, 110 said parts being arranged to normally permit the plow to move from a raised to a lowered position, and said supporting means comprising means for raising and lowering the plow, means for holding said raising and lowering means in a predetermined position, and means for releasing said holding means and for automatically reengaging it 115 at variable and predetermined points to determine the depth of a furrow to be plowed. 120

3. A plow with means for supporting it, 125 said parts being arranged to permit the plow to move from a raised to a lowered position, a lever for raising and lowering the plow, and said supporting means comprising a detent on said lever, a holding rack to receive said detent, a latch lever having a trip to re-

lease said detent to permit its reengagement with the holding rack, and means for operating the latch lever.

4. A plow with means for supporting it, said parts being arranged to permit the plow to move from a raised to a lowered position, and said supporting means comprising a lever for raising and lowering the plow, a detent on said lever, a holding rack to receive said detent, a latch lever having a trip to release said detent to permit its reengagement with the holding rack, said detent moving independently of the latch lever in said reengaging movement, and means for operating the latch lever.

5. A plow with means for supporting it, said parts being arranged to permit the plow to move from a raised to a lowered position, and said supporting means comprising a lever for raising and lowering the plow, a detent on said lever, a holding rack for said detent, a latch lever, a rib on the latch lever serving as a trip and overlying a projection from the detent, said rib terminating at a point to disengage said projection and permit reengagement of the detent with the holding rack, and means for operating the latch lever.

6. A plow with means for supporting it, said parts being arranged to permit the plow to move from a raised to a lowered position, and said supporting means comprising means for raising and lowering the plow, means for holding the plow in a raised position, means for automatically controlling its movement from a raised to a lowered position, and means for releasing said holding means and for permitting its reengagement at a predetermined point.

40 7. A plow with means for supporting it, said parts being connected and arranged to normally move the plow from a raised to a lowered position, and said supporting means comprising means for raising and lowering the plow, means for automatically governing its movement from a raised to a lowered position, means for holding it in a raised position, and means for releasing said holding means and for permitting its reengagement with its coöperative member at variable predetermined points.

8. A plow frame including wheels for movably supporting it, a plow movably supported thereon, means tending to normally lower the plow, a train of gears operatively connected with one of said wheels, and means for bringing said train of gears into operation to control the lowering movement of the plow.

60 9. A plow frame including wheels for supporting the same, a plow movably supported thereby, means tending to normally lower the plow, a lever for raising and lowering the plow, a train of gears operatively connected

with one of the wheels and also with the plow lowering and raising mechanism, and means for bringing said gears into operation to control the lowering movement of the plow.

10. A frame including wheels for supporting the same, a plow movably supported thereby, means tending to normally lower the plow, plow raising and lowering means, a train of gears operatively connected with one of said wheels and with said plow raising and lowering means, means for holding said raising and lowering means in a predetermined position, and means for simultaneously releasing said holding means and for engaging said gears to control the lowering movement of the plow.

11. A plow with means for supporting it, a lever handle for raising and lowering the plow, a supporting wheel, a train of gears supported by said lever and meshing with a gear on said supporting wheel, means for holding said lever in a predetermined position, a gear rack adapted to mesh with one of said gears, means for releasing said holding means, and means for causing engagement of the gear rack and train of gears.

12. A plow with means for supporting it, a lever for raising and lowering the plow, a supporting wheel, a gear secured thereto, a train of gears meshing with the gear on the supporting wheel, means for holding the lever in a predetermined position, a gear rack adjustably mounted on the frame, and means for engaging the rack with said train of gears and for disengaging said holding means.

13. A plow, means for supporting the plow including a supporting wheel, a lever for raising and lowering the plow, a gear on said supporting wheel, a train of gears mounted on the lever and meshing with the gear on the supporting wheel, a holding rack, a dog on said lever handle adapted to engage said holding rack, a gear rack pivotally supported, means for engaging the gear rack with one of said gears, and a trip on the gear rack arranged to disengage said dog from the holding rack.

14. A plow with means for supporting it and including a supporting wheel, a gear secured to said wheel, a lever handle, a train of gears supported by the lever handle and in mesh with the gear on the supporting wheel, a holding rack, a dog on the lever arranged to engage notches in the holding rack, a gear rack pivotally mounted, a pin rigidly connected with the dog, and a trip on the holding rack overlying said pin, said trip terminating with respect to the notches in the gear rack to permit engagement of the dog with its recesses upon disengagement of a gear from the gear rack.

15. A plow with means for supporting it, a lever for raising and lowering the plow, a

train of gears supported by the lever and operatively connected with a movable part of the frame supporting the plow, means to engage said gears to move the lever to regulate the vertical movement of the plow, a

pedal and said gear engaging means to operate the latter.

RALPH E. GOULD.
